ADHESIVE TERMINAL FOR TAPE MEASURES

Abraham Berkovic, Philadelphia, Pa.

Application July 11, 1952, Serial No. 298,264

3 Claims. (Cl. 33—137)

1

This invention relates to terminals or handles for tape measures and other measuring devices, such as yard sticks and rulers, and more particularly to a terminal which will releasably adhere to textile fabrics and maintain the corresponding end of an associated measuring device at a selected position relative to a piece of fabric being measured.

It is among the objects of the invention to provide an improved terminal handle for a tape line or measure which can be placed on a piece of textile fabric and will adhere to the fabric at the selected locations so that the associated tape measure can be stretched from the handle to measure the fabric without moving the handle relative to the fabric; which does not damage the fabric in any way and can be quickly and easily removed from the fabric when desired; which is detachably connected to a tape measure so that the tape measure can be replaced when desired; which is of light weight and small size and easy to handle by an operator, such as a tailor fitting garments to customers; which provides a reel or spool on which the tape measure can be wound for convenience in transportation and storage; and which is simple and durable in construction, and economical to manufacture, positive and effective in use, and neat and attractive in appearance.

Other objects and advantages will become apparent from a consideration of the following description and the appended claims in conjunction with the accompanying drawing wherein:

Figure 1 is a somewhat diagrammatic elevational view showing the terminal handle and an associated tape measure applied to a garment worn by a person or model;

Figure 2 is a bottom plan view of the terminal handle;

Figure 3 is a longitudinal cross sectional view on the line 3—3 of Figure 2;

Figure 4 is a fragmentary cross sectional view on the line 4—4 of Figure 3;

Figure 5 is a fragmentary cross sectional view on the line 5—5 of Figure 2; and

Figure 6 is an exploded perspective view of the terminal handle and associated tape measure.

With continued reference to the drawing, the tape measure or tape line 10 is of well known form, such as is conventionally used by tailors and dressmakers, and may comprise a length of fabric tape having indicia of lineal measurement imprinted thereon. Such tapes are usually from one-half to three-quarters of an inch in width and may have a length of from three to six feet

2

divided by the indicia thereon into feet, inches and fractional parts of inches.

The terminal handle, generally indicated at 11, is preferably formed of a suitable material, such as a synthetic resin plastic, by a suitable molding or die-casting operation and includes a hollow housing 12 and a substantially solid body 13 removably disposed in the housing 12.

The housing 12 is a thin walled structure of 10 elongated, rectangular cross sectional shape and includes flat faced walls 14 and 15 disposed in spaced apart relationship and substantially parallel to each other transversely of the housing and side walls 16 and 17 extending between the 15 corresponding edges of the face walls 14 and 15, the side walls having a width materially less than the face walls. The housing 12 is open at both ends and tapers in both width and thickness from a location adjacent one end to the other end 20 thereof, the side walls 16 and 17 preferably being concavely curved. At the smaller end of the housing the side walls 16 and 17 are extended to provide spaced apart tabs 18 and 19 of substantially semi-circular shape and the face wall 14 25 terminates somewhat short of the remaining walls at the larger end of the housing and is provided in its end at the larger end of the housing with a notch 20 of rectangular shape having a length only slightly less than the width of the 30 larger end of the housing and a width of at least one-half its length.

The face wall 15 is provided with transversely extending slots 21 and 22 disposed one near the smaller end and one near the larger end of the 35 housing and substantially perpendicularly bisected by the longitudinal center line of the housing wall 15. These slots 21 and 22 have a length slightly greater than the width of the tape measure 10 and the tape measure extends through these slots at spaced apart locations adjacent the end thereof carrying the zero end of the scale of lineal measurement thereon. Between each of the slots 21 and 22 and the adjacent ends of the housing 12 the tape measure is disposed at the inner side of the wall 15 of the housing and between the slots it is disposed at the outer side of the housing wall, as illustrated in Figure 3.

The body 13 is also of elongated, rectangular cross sectional shape and may comprise a solid body or a hollow shell having a core or filter therein, as illustrated in Figures 3 and 4, and is tapered from one end to the other. It fits closely into the housing 12 and has at its smaller end laterally projecting detents 23 and 24 which engage shoulders 25 and 26 at the smaller end

of the housing with a snap action to secure the body 13 in the housing. At its larger end the body 13 is provided with a recess 27 of rectangular shape which registers with the notch 20 in the face wall 14 of the housing with the body 13 fully received in the housing and is provided at its larger end with an end wall 28 having a flange 29 which overlies the adjacent end of the recess 27. A rectangular block 30 of a perforable and somewhat resilient material, such as felt, is disposed in the recess 27 and has one edge received in a groove 31 provided in the body adjacent the back wall 32 of the body and at the side of the recess 27 remote from the end wall 28. The back wall 32 closes the side of the recess 27 remote from the housing wall 14 and provides a support for the block 30.

At its edge remote from the groove 31 the block 30 bears against the inner side of the end wall 28 and a plurality of wire staples 33 are secured in the block with their intermediate portions against the inner side of the back wall 32 of the body 13 and their legs projecting perpendicularly from the side of the block 30 remote from the back wall 32. These legs 34 terminate in pointed ends disposed substantially in the plane of the outer surface of the face wall 14 of the housing and the outer end portions of the legs 34 of the staples are inclined in a direction away from the flange 29 of the end wall 28, as illustrated in Figure 3.

The legs 34 of the staples 33 constitute pins which extend substantially perpendicularly from the block 30 in uniformly spaced apart and substantially parallel relationship to each other and are engageable at their outer, pointed ends with the fibres of a piece of textile fabric, such as the garment 35 illustrated in Figure 1, to cause the terminal handle 11 of the tape measure to releasably adhere to the fabric so that the tape measure 10 can be stretched from the handle to measure the piece of fabric.

Buttons 36 and 37 are secured one to each of the side walls 16 and 17 of the handle near the larger end of the handle to provide finger grips for conveniently applying the handle to and removing it from a piece of fabric to be measured and the staple legs or pins 34 are formed of wire of very small diameter in proportion to the area of the notch 20 in the housing 12, this wire being of substantially the same diameter as that used for carding needles in wool or cotton carding machines, and the group of pins or staples will adhere firmly to a piece of textile fabric without damage to the fabric. The inclination of the outer ends of the pins causes the pins to set deeper into the fabric when a pull is exerted on the tape measure 10 and enable the handle to be easily released from the fabric without damage thereto by moving the handle outwardly from the fabric and in a direction opposite the direction of the pull of the tape measure on the handle.

In using the device the terminal handle can be caused to adhere to the fabric at any desired location leaving both hands of the operator free to hold the tape line and apply chalk marks, pins or other markers to the fabric being measured.

The two lugs 18 and 19 constitute guides for holding the tape measure on the smaller end of the handle when the tape measure is wound

around the handle over the smaller end of the housing 12 and over the end wall 28 of the filler body 13 to provide a compact package for transportation or storage. When the tape measure is wound on the handle it covers the outer ends of the pins or staples 34 so that, in this condition, the device may be carried in the pocket, if desired, without adhering to the pocket lining.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims, are therefore, intended to be embraced therein.

What is claimed is:

1. A handle for a tape measure comprising a hollow housing of elongated shape having open ends and a notch at one end thereof and adapted to be connected to a tape measure in a manner such that the tape measure extends from the other end of said housing, a body of elongated shape received in said housing and having at one end a recess registering with said notch in the housing, and means disposed in the recess in said body and exposed through the notch in said housing effective to cause said handle to adhere to an object to be measured by the associated tape measure.

2. A handle for a tape measure comprising an elongated body having at one end a recess having an open side and adapted to be connected to a tape measure in a manner such that the tape measure extends from the other end of said body, a flat block disposed in said recess and secured to said body, and a plurality of pins disposed in said recess in spaced apart and substantially parallel relationship to each other and secured each at one end to said block, said pins having their other ends disposed substantially in a common plane parallel to the adjacent face of said flat block and exposed at the open side of said recess for engaging a body of textile fabric and causing said handle to adhere to the fabric body.

3. A handle for a tape measure comprising an elongated body having at one end a recess having an open side and adapted to be connected to a tape measure in a manner such that the tape measure extends from the other end thereof, a hollow housing receiving said body and having therein a notch registering with said recess, a flat block disposed in said recess and secured to said body, and a plurality of pins disposed in said recess in spaced apart and substantially parallel relationship to each other and secured each at one end to said block, said pins extending at their other ends through the notch in said housing and adapted to engage a body of textile fabric to cause said handle to adhere to the fabric body.
